THRESHOLD WEATHER STRIP

William B. Bailey, Olympia, Wash.

Application November 11, 1935, Serial No. 49,286

6 Claims. (Cl. 20—58)

This invention relates to improvements in threshold weather strips for use in preventing drafts beneath a door bottom and threshold and excluding dust, rain, snow, light, etc., and particularly to a vertically movable strip which is projected downward to an operative position for contact with the threshold when the door is closed and raised to an inoperative position when the door is opened.

10 One object of the invention is to provide a neat and attractive construction of automatically operating strip which is applicable to either the inner or outer face of the door or to bottom grooves of doors, which is so mounted as to be raised quickly at the moment of opening of the door and lowered at the moment of closing of the door so as to avoid rubbing friction between the strip and floor surface at all other times in the opening and closing movements of the door.

15 A further object of the invention is to provide a strip which will automatically accommodate itself to unevenness of surfaces of threshold strips and variations in the distance between a threshold strip and bottom edge of the door, and which may additionally be manually adjusted to compensate for any extraordinary variations of such character which may occur in making an installation.

A still further object of the invention is to provide a strip which is applicable with equal facility to right or left hand outwardly or inwardly swinging hinged house and doors of other buildings, including ordinary swinging doors, double action doors, wood or metal and metal frame doors, and doors of the accordion type such as used on garages, lubricating rooms of automobile service stations, store fronts, etc.

A still further object of the invention is to provide an automatic threshold strip for doors which is simple of construction, reliable and efficient in use, not liable to easily get out of order, and which may be installed and kept in proper service condition at a comparatively low cost.

With these and other objects in view, the invention consists of the features of construction, combination and arrangement of parts, herein-after fully described and claimed, reference being had to the accompanying drawings, in which:—

50 Fig. 1 is an elevational view showing the application of the invention upon the inner side of a door.

Fig. 2 is a horizontal section on line 2—2 of Fig. 1.

55 Fig. 3 is a view similar to Fig. 1 showing the ap-

plication of the invention to the outer side of a door.

Fig. 4 is a horizontal section on line 4—4 of Fig. 3.

Fig. 5 is a detail view looking toward the hinging jamb of the door frame and the hinging edge of the door structure illustrated in Figs. 3 and 4, showing parts of the invention mounted thereon.

Fig. 6 is a vertical longitudinal section through the strip holder and parts of the door, showing the strip in its inoperative or retracted position.

Fig. 7 is a similar view showing the strip in its projected position.

Fig. 8 is a cross-section on line 8—8 of Fig. 7.

Fig. 9 is a perspective view of the strip actuating contact or device employed in the structure shown in Figs. 1 and 2.

Figs. 10 to 12, inclusive, are sections illustrating the movements of the strip actuating contact shown in Figs. 1, 2, and 9 in the movements of the door.

Fig. 13 is a view showing the application of the invention to a door having a bottom groove in which the threshold strip is mounted.

Fig. 14 is a cross-section on line 14—14 of Fig. 13.

Fig. 15 is a view of one of the strip retainers used therein.

Fig. 16 is a fragmentary view showing a contact for use on a door section of an accordion or multiple section door for actuating the strip on another door section.

Fig. 17 is a fragmentary view showing the use of an adjustable contact for use particularly on doors hung on metal frames.

Fig. 18 is a view of the contact shown in Fig. 17.

Referring now more particularly to Figs. 1 and 3 to 12, inclusive, 1 designates a door frame having a threshold 2 and on which is mounted a hinged door 3.

On the inner side of this door, adjacent to the bottom edge thereof, is mounted a channeled sheet metal casing 4, preferably formed of a folded piece of sheet metal, said casing being open at its bottom and ends and closed at its top and secured to the door by fastening screws 5. Disposed within this casing is a similarly formed sheet metal strip holder 6, in which is fitted the threshold strip 7 of felt, rubber or a combination of these materials, or other suitable flexible or resilient material. This strip 7 projects at its lower edge below the holder 6 and, as shown in the present instance, is removably and adjustably secured within the holder by providing the walls of the latter with indented pro-

5

sections 8 entering the body of the strip. These indented projections serve to hold the strip securely in place, but allow the walls of the holder to be bent outward to withdraw the indentations 5 from engagement with the strip when desired, so that an old and worn out strip may be removed and another substituted in its place or so that the strip may be adjusted in the holder and secured so as to be positioned to suit variations 10 in the distance between the threshold and bottom edge of the door, whereby the strip may be arranged to make a proper sealing contact when projected between the threshold and door regardless of variations in distance between the bottom 15 edge of the door and portions of the threshold throughout the length of the latter.

The strip and its holder are vertically movable in the casing so as to be projected downwardly to an operative position and moved upwardly 20 or withdrawn to an inoperative position. To this end, the holder 6 is pivotally connected, as at 9, to the free ends of a pair of swinging links or levers 10, the opposite ends of which levers are pivotally mounted by pivot members 11 on 25 the casing. The latter-named ends of the levers are also pivotally connected above and in line with the pivots 11, as at 12, to an actuating plunger rod, bar or strip 13 which is movable in opposite directions to transmit motion to the links to 30 project and retract the strip. The links or levers 10 are so mounted and proportioned that a comparatively small range of movement of the plunger 13 will result in a relatively greater range of movement of the free ends of the links or levers, 35 so that on an opening movement of the door the threshold strip will be quickly retracted from an operative to an inoperative position, while upon a closing movement of the door, and upon actuating motion being applied to the plunger, a quick 40 projection of the strip will be effected at the moment of closing of the door, but not before, by which means projection of the strip in extremes of movement of the door will be prevented and the contact of the strip with the floor 45 surface avoided so as to prevent undue wear thereon. In order to adapt the strip to be moved upwardly without interference to a fully retracted position, the upper edge of the holder 6 is provided with notches or recesses 14 to receive 50 and engage the pivot members 11, whereby a locking connection is also formed to prevent longitudinal shifting of the parts when in retracted position. It will be noted that the pivotal connections 9 between the strip holder and 55 the links 10 are arranged on one side of the transverse center of said holder and strip, whereby the strip is adapted to independently tilt vertically on said pivotal connections as a fulcrum to adapt the strip to adjust itself into equal sealing engagement at all points with the threshold when projected downwardly into contact therewith, whereby when the door is moved to closed position undue frictional engagement between the strip and threshold will be avoided and the strip 60 accurately and uniformly brought into sealing relation with the threshold.

The casing, strip and plunger extend across the door approximately the full width thereof, and the plunger is connected at its end adjacent 70 the hinge edge of the door with an actuating arm 15 resting on and movable in guiding engagement with a guide member 16, which may comprise one of the fastening screws 5. Carried by this arm 15 is a guide pin or spindle 17 slidably engaging a 75 guide member 18 on the casing, and disposed

about this pin between its guided end and its opposite end fastened to the arm is a coiled compression spring 19 which operates to hold the plunger and strip in retracted position and to resist movement thereof to projected position, 5 whereby at all times when the door is opened the threshold strip will be withdrawn into the casing so as to lie above the lower edge of the door.

Arranged upon the hinging jamb of the door is a contact member adapted to be engaged by the 10 arm 15 when the door is closed to transmit strip projecting motion to the plunger at the moment of closing movement of the door. This contact member comprises a plate 20 mounted intermediate of its ends upon a pivot member 15 21 which may be in the form of a staple securing a bracket plate 22 to said hinging jamb. This construction of the contact member or plate 20 provides a plate having oppositely extending arms 23 and 24, providing a contact member 20 capable of application to either jamb of the door frame for use as a contact member whether the door is hinged either to the right hand or left hand jamb of the door, in which uses the arms 23 and 24 may serve alternately as contact 25 arms engaged respectively by the strip plunger 15 and the door or by inverting the contact member the arm 23 may be arranged to engage the plunger contact 15 and arm 24 the hinged edge of the door in the mounting of the door 30 on either door jamb. If desired, a contact screw 24a may be applied to the hinged edge of the door to provide an adjustable contact member for engagement with arm 24, said screw being adjustable to take up any slack in loose installations between the arm 24 and hinged edge of the door. The bracket plate 22 is provided with a laterally projecting and angularly disposed stop and wear projection 25 and is likewise reversible so that said projection 25 may cooperate 40 either with the arm 23 or the arm 24 in the use of one or the other as a plunger contact arm. In the example shown in Figs. 1, 2, and 9 to 12, inclusive, in which the arm 23 is the plunger engaged arm and the arm 24 is adapted to be 45 engaged by the hinged edge of the door, the projection 25 is disposed in the path of outward swinging movement of the arm 23, that is, in the path of movement of said arm 23 toward the hinging jamb of the door, said projection 50 operating in the opening movement of the door as a stop to limit such outward movement of the arm 23 and the inward movement of the arm 24 toward the door and away from the hinging jamb of the door frame. The object in 55 this action of part 25 is to properly dispose the contact member 20, during a door opening movement, for action on the plunger arm 15 on a door closing movement. The projection 25 preferably seats within a beveled recess 26 formed 60 in the hinging jamb, so as to adapt the contact 20 to be brought to the proper angular position. By reference to Figs. 10 to 12, inclusive, the action of the contact 20 will be readily understood. When the door is closed, as shown in 65 Fig. 12, the contact 20, which is at this time in strip projecting position, lies parallel with the hinged edge of the door. When the door is swung open, at which time plunger 15 is in engagement with arm 23, the pressure of the 70 plunger on said arm causes the contact 20 to swing freely on its pivot 21, in which action arm 23 moves away from the plunger arm 15 and comes in contact with stop 25, whereby the contact member is released quickly from en- 75

gagement with the plunger arm, allowing the strip to return at once to retracted position, and the door to be opened without engagement of the plunger arm with the contact. When the 5 door is again swung to closed position, the hinged edge of the door, at the moment of closing, engages the contact arm 24, as a result of which, in the final closing movement of the door, the contact member 20 is swung to the position 10 shown in Fig. 12 from that shown in Fig. 11, thus bringing contact arm 23 into engagement with the plunger arm 15, whereby the threshold strip is projected at the moment of closing of the door.

15 From the foregoing description of the construction and operation of the strip, it will be seen that as long as the door is open and the arm 15 is out of engagement with the contact member 20, the threshold strip will be held raised 20 or withdrawn to an inoperative position by the reaction of the spring 19, but that in the swinging movement of the door to closed position, and at the time when the free edge of the door moves into engagement with the threshold, the outer 25 end of the plunger arm 15 will be brought into engagement with arm 23 of the contact member 20, with the result that in the final closing movement of the door the plunger rod will be actuated to quickly project the strip into engagement with 30 the threshold. In its projecting movement, it will be understood, the strip is forced downward in a substantially straight vertical path by the action of the plunger and motion transmitting links, but it is permitted by reason of the arrangement of its pivotal connections with the 35 links, to tilt vertically on said pivotal connections and link as a fulcrum, so as to automatically adjust itself to irregularities in the level of different portions of the threshold, if such be 40 present, so that undue wear of the strip will be avoided and the strip will automatically seat itself into snug sealing engagement with the threshold. The strip when in operative position will effectually close the joint or space between the 45 lower edge of the door and the threshold against passage of drafts of air or dust and entrance of rain, snow, or foreign elements of any kind between the door and threshold. In the mounting of the door on the door frame to swing outwardly 50 instead of inwardly, a contact plate 21 may be employed in place of the contact member, said plate being secured to the hinging jamb of the door frame adjacent its outer face by means of a fastening screw 28 and a combined fastening and 55 contact screw 29, the latter serving to engage the outer end of the arm 15 to actuate the plunger 13 when the door is closed and being adjusted so that a nicety of contact action can be obtained.

Fig. 1 particularly shows the application of the 60 invention to the inner side or face of the door 3 but, if desired, and as shown in Fig. 3, the strip may be applied to the outer side or face of the door, which variations in arrangement may be made without alteration of the structure in any 65 particular, and in either of these applications the contact 20 or contact 21 may be employed accordingly as the door is mounted on the door frame to swing inwardly or outwardly. These 70 parts are also interchangeable in arrangement and for use whether the door is hinged to the right hand or left hand jamb of the door frame. The movements of the strip between inoperative and operative positions is shown in Fig. 7, from 75 which an understanding of the capability of the

strip to tilt to adjust itself to the threshold will be readily understood.

The threshold strip, as shown in Figs. 13 and 14, is also applicable to a door having a bottom groove or slot 30 to receive it and in which 5 it is movably mounted. This groove or slot extends the full width of the door and is of equal depth and width throughout its length. At the end of the groove or slot opening through the hinged edge of the door the end of the plunger 10 arm is exposed for engagement with the closing contact on the hinging jamb of the door frame. The strip holder or casing is retained in position within the groove or slot by retaining elements 31 secured to the hinging and swinging 15 edges of the door. Each of these retaining elements comprises a bracket plate folded upon itself at its upper end to provide a doubled attaching portion 32, the body of the bracket plate between this doubled portion and the opposite 20 end of the plate being bifurcated or provided with a slot 33 in line with the groove or slot in the door. The doubled end of the bracket plate and the arms of its bifurcations are provided with 25 openings for the passage of screws or other fastenings 34 to secure it to the door. The folded over end portions of the bracket plates are formed with spaced projections 35 extending into the ends of the door groove or slot and above the 30 upper and lower surfaces of the top wall of the 35 casing 4 to support said casing and the strip in said door groove or slot.

The threshold strip is also applicable for use on revolving doors or multiple doors, that is, doors of the accordion type composed of sections 35 hinged to each other and to a jamb of the door frame, in which case a threshold strip is applied to the bottom of each door section. With such an arrangement, a strip closing contact for actuating the strip on the door section hinged to the 40 jamb of the door frame will be actuated by a contact member on the hinging jamb, as previously described, while a special contact member will be provided upon the free edge of each door section for actuating the strip upon another 45 door section hinged thereto. This special form of contact member may be of the type shown in Fig. 16, in which the free edge of a door section 3a is shown as provided with a contact member 36 for actuating the plunger of the threshold 50 strip upon another door section 3b hinged to said free edge of said section 3a. This contact member 36 may be of suitable structure and mounted within the casing of the threshold strip on the door section 3a. As shown in the present instance, the contact 36 may be adjustable so that 55 it may be properly positioned for use, being provided for this purpose with a slot 37 receiving a fastening screw or other element 38 securing it in place. By such arrangement of threshold 60 strips upon the door sections and the provision of actuating contacts as described, the threshold strips upon all the door sections may be simultaneously operated, as will be readily understood.

The threshold strip may be applied to metallic doors and door frames in any of the ways described. It may be found desirable, however, where the door frame is made of metal and the door of either wood or metal, to provide a special type of contact to be mounted on the door instead of upon the door frame. A contact member 39 of this type is shown in Figs. 17 and 18, which contact member is of bell crank form and comprises a contact arm 40 and a pivot arm 41, the latter having perforated ears 42 bent out- 75

wardly therefrom to receive an adjusting and fastening screw 43 whereby said contact member is pivotally mounted on the door or the strip casing to swing upward and toward and from the free end of the plunger arm 18. This contact member is arranged so that as the door closes arm 40 will be swung toward the plunger arm to force the same inwardly and thereby communicate motion to the threshold strip to project the same. Preferably arm 40 is U-shaped to form a body portion 40a integral with the arm 41 and a contact portion or limb 40b integral at its lower end with the lower end of the portion 40 and forming an adjustable contact plate. This plate is adjustable with relation to portion 40a by means of a wedge piece 40c slidably held between parts 40a, 40b so that the contact plate may be adjusted to compensate for varying distances between the door frame and door due to warping of the door or other causes. Such a type of contact may in some cases be used on the door frame instead of on the door as will be readily understood. Any other suitable type of contact for this purpose may be employed according to conditions of use, so that by the provision of special contacts and retainers, some of which are particularly disclosed, the threshold strip, without change in the construction of the strip itself, may be applied to all types of doors made of wood, metal or composite materials.

If desired, a supplemental spring means may be provided to act on the end of the plunger 13 at the swinging edge of the door to assist the spring 19 in retracting the strip holder 6 and strip 1. This comprises a stem 17' slidable at one end in a guide member 18' fastened in place as by one or more of the screws 5, said stem bearing at its opposite end against the adjacent end of the plunger 13. A coiled spring 19' disposed about the stem between the member 18' and plunger 13 acts thereon to assist spring 19 in raising the strip to retracted position when the door is open.

From the foregoing description, taken in connection with the drawings, the construction, mode of operation and various applications of my novel and improved threshold strip will be readily understood, and it will be seen that a strip is provided which officially carries into practice the stated objects of my invention and which when in use will effectually adjust itself to the threshold to seal the space between the same and the bottom edge of the door against passage of drafts of air, rain, snow, and other material. While the structural organization shown is preferred, it will, of course, be understood that this is merely exemplificative and that changes in the form, construction, and arrangement of the parts within the scope of the appended claims may be made without departing from the spirit or sacrificing any of the advantages of the invention.

What I claim is:

1. In a threshold strip for doors a casing on the door, a strip vertically movable in said casing, a plunger mounted for longitudinal movement in the casing to project the strip for use, spring actuated means connecting the plunger with the casing for normally maintaining the strip and plunger in retracted position, pivotal connections between the strip and plunger for transmitting motion to the former from the latter, and a pivoted contact on the door frame having a door engaging portion on one side of its pivot and a plunger engaging portion on the other side of its

pivot for successive engagement with the door and plunger on a closing movement of the door.

2. The combination with a door frame and door, of a threshold strip mounted for vertical movement on the door, a plunger mounted on the door, connecting means between the strip and plunger for actuating the former from the latter, spring means for normally maintaining the strip and plunger in retracted position, and a pivotally mounted contact member on the door frame adapted to be engaged by the door on its closing movement and to be thereby moved into the path of the plunger for actuating the plunger at the final point of the door closing movement.

3. The combination with a door frame and a door, of a threshold strip mounted for vertical movement on the door, a plunger mounted on the door, connecting means between the plunger and strip for operating the latter from the former, spring means for normally maintaining the plunger and strip in retracted position, and a swinging contact element on the door frame engageable successively by the door and plunger for actuating the plunger.

4. A threshold strip for doors comprising a casing adapted to be mounted on the door, a strip member movable vertically in the casing, a plunger adapted to be actuated by contact with a portion of the door frame for projecting the strip member into engagement with the threshold of the door, and pivotal connections between the strip member and plunger for actuating the former from the latter, said pivotal connections being pivotally coupled at one end to the casing and to the plunger and at their opposite ends to the strip member, the latter-named ends of the pivotal connections being pivoted to the strip on one side of the transverse center of said strip.

5. A threshold strip for doors comprising a casing adapted to be mounted on the door, a strip member movable vertically in the casing, a plunger adapted to be actuated by contact with a portion of the door frame for projecting the strip member into engagement with the threshold of the door, and angularly arranged links pivotally connecting the strip member with the plunger for actuating the former from the latter, said links being pivotally connected at one end with the casing and plunger and at their opposite ends to the strip member, the pivotal connections between the links and strip members being arranged at one side of the transverse center of the latter to form fulcrums on which the strip member may tilt vertically on said pivotal connections to accommodate itself to variations from the horizontal of the threshold of the door.

6. A threshold strip for doors comprising a casing, a strip vertically movable in said casing, a plunger mounted for longitudinal movement in the casing and adapted to be actuated by contact with a part of the door frame to project the strip into engagement with the threshold of the door, and links of triangular form pivoted at the corners of their basal edges to the casing and to the plunger respectively and at their vertices to the strip for transmitting motion to the former from the latter, the latter-named ends of the links being pivoted to the strip on one side of the transverse center of the strip to adapt the strip to tilt vertically on said pivots to accommodate itself to variations from the horizontal of the threshold of the door.

WILLIAM B. BAILEY.
